The ornamental design for a connector, as shown and described.

DESCRIPTION

FIG. 1 is a front elevational view of the first configuration of a connector showing our new design;
 FIG. 2 is a rear elevational view thereof;
 FIG. 3 is a right side elevational view thereof;
 FIG. 4 is a left side elevational view thereof;
 FIG. 5 is a top plan view thereof;
 FIG. 6 is a bottom plan view thereof;
 FIG. 7 is a cross-sectional view thereof taken along a line 7-7 in FIG. 1;
 FIG. 8 is a perspective view showing a front, top and right side thereof;
 FIG. 9 is a perspective view showing a rear, bottom and left side thereof;
 FIG. 10 is a perspective view showing a front, right and bottom side thereof;
 FIG. 11 is a perspective view showing a rear, left and top side thereof;
 FIG. 12 is a front elevational view of the second configuration of a connector showing our new design, wherein a hinge portion is in a closed state;

(Continued)

FIG. 13 is a rear elevational view thereof;
FIG. 14 is a right side elevational view thereof;
FIG. 15 is a left side elevational view thereof;
FIG. 16 is a top plan view thereof;
FIG. 17 is a bottom plan view thereof;
FIG. 18 is a cross-sectional view thereof taken along a line
18-18 in FIG. 12;
FIG. 19 is a perspective view showing a front, top and right
side thereof;
FIG. 20 is a perspective view showing a rear, bottom and left
side thereof;
FIG. 21 is a perspective view showing a front, right and
bottom side thereof; and,
FIG. 22 is a perspective view showing a rear, left and top
side thereof.
The broken line showing of the connector is for the purpose
of illustrating portions of the article and forms no part of the
claimed design.
